UNITED STATES PATENT OFFICE.

JOHN JOSEPH MAHONEY, OF TAUNTON, MASSACHUSETTS.

DOUBLE-ACTING FAUCET.

Application filed August 2, 1921. Serial No. 489,180.

To all whom it may concern:

Be it known that I, JOHN J. MAHONEY, a citizen of the United States, residing at Taunton, in the county of Bristol and State of Massachusetts, have invented certain new and useful Improvements in Double-Acting Faucets; and I do hereby declare the following to be a full, clear, and exact description of the invention, such as will enable others skilled in the art to which it appertains to make and use the same.

The present invention relates to improvements in double acting faucets which are self-closed for use in the distribution of hot and cold water, and the invention has for an object to provide a simple, compact and inexpensive construction of faucet with a double acting valve structure operable by a single handle and controlling the flow of both hot and cold water, with devices to keep the valves in an open or partially open position until manually released, whereupon the device is restored to the initial closed position.

Another object of the invention resides in the provision of a faucet of this character, in which independent water boxes are provided in communication individually with sources of hot and cold water, wherein independently movable valves are provided to control the flow of water to a common nozzle or spout.

The invention will be more fully understood after reference to the accompanying drawings, in which like parts are indicated by similar reference symbols throughout the several views, and in which:—

Figure 1 is a view in side elevation of an apparatus constructed according to the present invention.

Figure 2 is a vertical sectional view therethrough.

Figure 3 is a sectional view taken at right angles to Figure 2; and

Figure 4 is a sectional view taken on the line 4—4 in Figure 1.

Referring more particularly to the drawings, 1 designates a nozzle or spout which communicates in common with the two water boxes 2 and 3. A pipe 4 in communication with a source of cold water leads to the water box 2, while the companion water box 3 is in connection with a source of hot water supply by a pipe 5.

The bottoms of the water boxes 2 and 3

form a septum or diaphragm cutting the water boxes off from communication with the spout or nozzle, except such water as may issue through the ports 6 and 7, under the control of the valve plungers 8 and 9. These plungers carry valve washers 10 and 11 of compressible material which are adapted to seat tightly against the raised valve seats 12 and 13 on the interior bottom portions of the water boxes. Compressible valve disks 10 and 11 are held on the plungers 8 and 9 as by the screws 14, but, of course, other suitable fastening means may be substituted. The valve disks 10 and 11 may be thus disconnected from the plungers when worn, and replaced.

Cylinders or sockets 15 and 16 depend from the top plates 17 and 18 of the water boxes, and are provided to slidably receive the plungers 8 and 9 which reciprocate in a substantially vertical direction, they being urged normally downward by coil springs 19 and 20, wound about reduced stems 21 and 22 which extend upwardly from the plungers and form shoulders therewith, upon which the lower ends of the springs rest.

Links 23 and 24 connect the upper projecting ends of the stems 21 and 22 with curved arms 25 and 26, adapted to be operated separately by a common centrally disposed handle 27.

As more particularly shown in Fig. 3, the handle 27 is made with a bearing sleeve 28 rotatable freely upon a rod or shaft 29 which is preferably in the form of a screw having threads 30 at one end, screwed into a threaded lug 31, secured to the top of the device and having its head 32 disposed on the outside of a second stationary and perforated lug 33. The bearing sleeve 28 is provided with right angularly turned lugs 34 and 35 which are adapted to engage pins 36 and 37 on the bearing sleeves 38 and 39, respectively, of the curved arms 25 and 26. This construction is most plainly seen in Fig. 4. The arms are upwardly curved where they connect with the links 23 and 24 to adapt them to swing down in the closing movement of the valve, and to lift freely in raising the valves. Moreover, the outer overhanging ends of the arms 25 and 26 lie beyond the sides of the water boxes and are turned down to a low point in order to connect with bolts or catches 40 and 41 which have a

swinging movement about the arms and are adapted to engage with rack teeth 42 and 43 carried at the sides of the water boxes.

In the use of the device cold water from the pipe 4 constantly occupies the water box 2, while hot water received through the opposite pipe 5 is contained in the adjacent water box 3, but neither supply of water is permitted to descend into the faucet 1 because of the initially closed position of the two valves.

The springs 19 and 20 are responsible for this closed position, and they restore the valves to their seats after each opening movement, provided the catches 40 and 41 are released. When hot water is desired for instance, the handle 27 is swung to the left, thereby causing the lug 34 to ride downward against the pin 36 and raise the arm 26. With the arm, the valve plunger 9 is also lifted and hot water may then descend through the ports 7 and issue from the faucet 1. The engagement of the pawl or catch 41 with the rack teeth 43 will prevent the immediate return of the valve to its seat by reason of the influence of the spring 20, and consequently the device may be kept in this position without the continued attendance of the operator. When a sufficient supply of water has been had, the catch 41 is released and the valve 9 automatically closes. By swinging the handle 27 to the opposite side of the device, the cold water valve 8 will be opened and a supply of the latter made to issue through the faucet.

It will be obvious that various modifications might be made in the herein described device, and in the construction, combination and arrangement of parts which could be used without departing from the spirit of my invention; and I do not mean to limit the invention to such details except as particularly pointed out in the claims.

Having thus described my invention what I claim and desire to secure by Letters Patent of the United States is:—

1. In a faucet, adjacent water boxes separately in communication with sources of hot and cold water supplies, a nozzle having controlled communication with the water boxes, reciprocating valves in the water boxes, spring means for normally closing the

valves, arms connected to individually raise the valves, means for pivoting said arms in common for individual rocking movement, a handle intermediate the arms having means thereon and in conjunction with the arms for raising one or the other of the arms accordingly as the handle is swung in the one or the other direction, and catches carried by the outer ends of the arms for holding the valves in a desired open position, substantially as described.

2. A faucet comprising a nozzle, separate chambers communicating independently with the nozzle and being in communication with source of hot and cold water supplies, valves for controlling the communication between the chambers and nozzles, means whereby valves are normally seated, arms pivoted together on the faucet and movable independently of one another, means connecting said arms separately with the valves, operating means swinging on the same center with said arms and having means arranged therebetween and between said arms for rocking the one or the other arm accordingly as the operating means is swung into one or the other direction, and catch means to hold the valve open independently of the position of the operating means, substantially as described.

3. A faucet comprising a nozzle, water boxes carried by said nozzle and opening independently into the same, valves in said water boxes for controlling the communication with the nozzle, yieldable means for normally urging the valves to a closed position, a pivoted pin carried by the faucet, arms having bearing sleeves mounted for independent free turning movement at opposite ends of said pin, said bearing sleeves having projections in relatively opposite direction, a handle having a bearing sleeve mounted on the pin between said arm bearing sleeves and having angularly projecting lugs to independently engage said projections, means for loosely coupling intermediate parts of the arms to said valves, pivoted catches carried by the outer ends of the arms, and racks cooperating with the catches and carried by the sides of the faucet, substantially as described.

JOHN JOSEPH MAHONEY.
